UNITED STATES PATENT OFFICE.

FRANK T. CORTESE, OF BROOKLYN, NEW YORK.

EDUCATIONAL TOY.

Application filed April 25, 1923. Serial No. 634,521.

To all whom it may concern:

Be it known that I, FRANK T. CORTESE, a citizen of the United States, residing at Brooklyn, in the county of Kings and State 5 of New York, have invented certain new and useful Improvements in Educational Toys, of which the following is a specification.

This invention relates to improvements in 10 toys and has for its primary object to provide a toy that will develop the power of concentration, memory, attention, etc. in children, and one that will prove interesting and also instructive to grown-ups.

15 A further object of the invention is to provide an educational toy which can be used for the teaching of the Morse code and one that will permit the sending of visible dots and dashes as are employed in the 20 Morse code of signaling.

25 A still further object of my invention is to provide a toy of the above indicated character, which is simple in construction, efficient for the purpose intended, and one that can be folded into a compact position when not being used so that same can be easily transported or stored away into a relatively small space.

30 And a still further object of my invention is to provide an educational toy of the character indicated, which can be manufactured and sold at a relatively low cost.

These and like objects of the invention 35 will be better understood as the description follows and as is specifically pointed out in the appended claims.

Referring to the accompanying drawings which form a part of this specification,

40 Figure 1 is a perspective view of a toy constructed in accordance with my invention.

Figure 2 is a front elevation, and

Figure 3 is a side elevation.

Referring to the accompanying drawings 45 in detail, like characters will be used to designate like parts in the different views.

In the drawings, the numeral 5 indicates a base for the mounting of my toy. It is to be understood that the base 5 is constructed 50 of any suitable material and made of any desired thickness, and when using my educational toy, the base 5 is adapted to be supported on a table, chair, etc.

55 A board 6 is positioned at one end of the base 5 and extends at right angles thereto.

Posts 7 having their upper portions cut away as at 8 are pivoted as at 9 to the front board 6 and each of the posts 7 are hingedly connected as at 10 to the base 5, and a clamp 11 carried by the underside of the 60 base cooperates with the hinges 10 for holding the front board in the position indicated in the accompanying drawings.

Levers 12 and 13 are pivoted to the posts 7 on the pivots 9 and each of the levers are 65 adapted to work through a stop 14 and each of the levers is provided on its inner end with a thumb piece 15.

The outer end of the lever 12 terminates 70 into a flat circular portion 16 which is adapted to indicate dots of the well known Morse code of signaling, while the lever 13 is of equal width throughout its entire length and is adapted to represent the dashes of the Morse code system. On the 75 inner side of the front board 6 as at 17 are printed in large characters the Morse code, while the front side of the board 6 is provided on one side with a color that corresponds with the color of the lever 12, while 80 the opposite side of the front of the board has a color that corresponds to the color of the lever 13.

In the operation of my educational toy, 85 the base 5 is supported on a table as above indicated, and the operator of the toy takes a position at the rear of same, while the parties to whom a message is to be transmitted stand at a spaced distance from the front of the board 6, and as the operator 90 presses on the thumb pieces 15 of the levers 12 and 13, same are allowed to move into view, thus indicating the dots and dashes of the Morse system for transmitting of messages.

When it is desired to transport my educational toy or store same away, the latch 11 is released, which allows the front board 6 carrying the levers to swing on the hinges 10 until same is moved to the position indicated by dotted lines in Figure 3.

In view of the foregoing description of my invention taken in connection with the accompanying drawings, it is thought that any further explanation as to the construction, operation, and objects of the invention is unnecessary.

While I have shown and described the preferred form of my invention, I realize that various minor changes may be resorted 110

to, without departing from the spirit and scope of the invention as claimed, and therefore, I do not wish to limit myself to the exact details of construction shown, nor to 5 the combination and arrangement of parts.

What I claim as new and desire to secure by Letters Patent is:

1. In an educational toy, comprising a base, a headboard connected to said base, 10 and means carried by one side of the headboard for sending a code message, said headboard so arranged that the code message may be read from the opposite side thereof.
2. In an educational toy, comprising a base, a headboard hingedly connected to said base and provided with a printed code, levers pivoted to one side of said headboard and adapted to represent the dots and dashes of a code, and means for moving said levers 20 into view for the sending of a code message.
3. In an educational toy, comprising a

base, a headboard connected to said base, a pair of levers pivoted upon one side of said headboard and adapted to be visible from the other side of said headboard for sending 25 a visible code message.

4. In an educational toy, comprising a base, a headboard connected to said base, and a pair of levers pivoted upon one side of said headboard, one of said levers having 30 a portion to represent a dash and the other a portion to represent a dot, said dot and dash portions on said levers adapted to be visible from the other side of said headboard for sending a visible code message. 35

In testimony whereof, I have affixed my signature in the presence of two witnesses.

FRANK T. CORTESE.
